(57) **CLAIM**

The ornamental design for the display screen with graphical user interface, as shown and described.

DESCRIPTION

Fig. 1 is a front plan view of a first embodiment of the claimed design;

Fig. 2 is a front plan view of a second embodiment of the claimed design;

Fig. 3 is a third embodiment of the claimed design;

Fig. 4 is a front plan view of a fourth embodiment of the claimed design;

Fig. 5 is a front plan view of a fifth embodiment of the claimed design;

Fig. 6 is a front plan view of a sixth embodiment of the claimed design;

Fig. 7 is a front plan view of a seventh embodiment of the claimed design; and

Fig. 8 is a front plan view of an eighth embodiment of the claimed design.

The claimed design is the visual features of the display screen with graphical user interface that are shown in solid lines and gray tones in the figures.

The outermost broken-line rectangle illustrates the perimeter a display screen or portion thereof and forms no part of the claimed design. The remaining broken lines illustrate portions of the graphical user interface that form no part of the claimed design. The text features which are blurred in the figures form no part of the claimed design.
